UNITED STATES PATENT OFFICE.

EDWARD SOULÉ, OF NEW YORK, N. Y., ASSIGNOR OF ONE-HALF TO EMIL BUFF, OF BROOKLYN, NEW YORK.

AUTOMOBILE-SIGNAL.

1,127,103.

Specification of Letters Patent. Patented Feb. 2, 1915.

Application filed August 12, 1914. Serial No. 856,342.

To all whom it may concern:

Be it known that I, EDWARD SOULÉ, a citizen of the United States, and a resident of the city of New York, borough of Brooklyn, in the county of Kings and State of New York, have invented a new and Improved Automobile-Signal, of which the following is a full, clear, and exact description.

This invention relates to automobile equipment and has particular reference to signaling devices therefor.

Among the objects of the invention is to provide a signal box or casing adapted to be carried preferably at the rear end of the chassis or limousine, and at either side or in the center thereof, depending upon the arrangement of the steering apparatus or upon the personal preference of the owners of the machines or requirements of the State or municipal ordinances.

More definitely stated, the object of the invention is to provide a series of movable signal members adapted to be brought into view selectively so as to indicate to a person following the machine having the signal that a turn is to be made to the right or to the left, or the vehicle is about to stop. It is obvious, also, that other signal members may be employed in addition to those indicated, if desired, carrying out the same important features of construction.

Another object of the invention is to provide a lamp for illuminating the signal members at night, the lamp being caused to glow simultaneously with the bringing into action of any one of the signal members.

A still further object of the invention is to provide an audible signal or alarm caused to be operated simultaneously with the action of the movable signal members, the lamp and audible signal being preferably so arranged that both may act at the same time or either of them may be made to act to the exclusion of the other.

The foregoing and other objects of the invention will herein later be more fully described and claimed and illustrated in the drawings forming a part of this specification in which like characters of reference indicate corresponding parts in all the views, and in which—

Figure 1 is a diagrammatic representation of an automobile having my signaling appliance secured thereto on the same side as

the steering mechanism; Fig. 2 is a vertical transverse sectional view through the signal box or casing on the line 2—2 of Fig. 3, one of the signal members being indicated in active position; Fig. 3 is a view as from the left side of Fig. 2, but with the face plate of the casing removed; Fig. 4 is a transverse section on the line 4—4 of Fig. 3; Fig. 5 is a perspective detail view of a preferred form of switch box adapted preferably to be secured within easy reach of the driver, as upon the hand wheel; and Fig. 6 is a diagram indicating the electrical connections.

The several parts of the device may be made of any suitable materials, and the relative sizes and proportions, as well as the general design of the mechanism, may be varied to a considerable extent without departing from the spirit of the invention hereinafter more fully set forth and specifically claimed.

Referring more particularly to the drawings I show a signal casing 10 secured in any desired manner in a permanent or stable position, preferably upon the rear end of an automobile and in position to be in clear view from the rear of the automobile.

The general apparatus includes a battery casing 11, a switch box 12 and any suitable collections or cables of wires 13 and 14 between the battery casing 11 and the switch box and signal casing respectively. Obviously the battery casing 11 may be carried in any convenient part of the machine and the cables 13 and 14 may be of any length and be directed along any suitable and convenient lines of the vehicle chassis or body.

By way of illustration of the possibilities of the invention, but without limiting the same unnecessarily by such illustration, I show a signal casing equipped with three movable arms 15, 16 and 17 representing respectively right, left and stop. As shown, these arms are mounted upon a common pivot 18 adjacent the upper end of the casing, the axis of the pivot extending longitudinally in a horizontal direction parallel to the direction of movement of the vehicle. Each arm is adapted to be moved outwardly around said pivot through a slot 15', 16' or 17' arranged in parallel vertical planes at the side of the casing. Each arm is held

normally in position within the casing, whereby either rattling or undesirable vibration of the arm is prevented by means of a catch 19 pivoted at 20. Each catch 5 is in the form of a lever of the first class and is acted upon by a spring 21 which serves to make the catch effective to engage with the outer lower corner of the arm, as shown in Fig. 2. The lever or catch 19 10 constitutes an armature in connection with a relay 22 through which the catch is released coincidentally with the swinging of the arm to horizontal position.

The main battery or source of power is 15 indicated at 23, and a solenoid 15^a, 16^a or 17^a is associated with each of the signal arms and in circuit with the battery. The battery circuit includes a strap 24 with which are connected any suitable switches 20 shown in the form of push buttons 15^b, 16^b and 17^b between which and the three signal arms are arranged circuits 15^c, 16^c and 17^c respectively. Each of these branch circuits includes also the relay 22 which 25 pertains to each separate signal device. Each of the solenoids includes a plunger or core 25 movable downwardly under the force of the solenoid and connected by means of a flexible member 26 over a wheel 30 or pulley 27. While the illustration shows a chain 26 and a mutilated sprocket gear 27, it is obvious that these elements may assume different specific forms without varying the operation or purpose of the 35 device. When any one of the three main switches is closed, as by pressing a button at the switch box 12, the corresponding core 25 will draw downwardly upon the chain 26 and simultaneously the relay 22 will release the catch 19, allowing the force of the 40 solenoid to swing the arm outwardly and upwardly through substantially 90 degrees. When the core 25 approaches or reaches the lower limit of movement, a dog 28 pivoted 45 at 29 is caused by action of a spring 30 to engage the upper end thereof to hold it in position to maintain the signal arm elevated. The action of the solenoid is much slower than that of the relay or magnet 50 22, and hence, while the current passes through both the magnet 22 and the solenoid at the same time, the power of the solenoid required to bring the arm positively into display position results from what is commonly termed the "building up action," 55 and before such power has time to be exerted upon the arm the magnet will have long since performed its function.

An audible signal in the form of an electric bell 31 is arranged in a branch circuit 32, and a lamp 33 is arranged in a circuit 34. These branch circuits 32 and 34 are provided with switch contacts 32' and 34' respectively, either or both of which may 60 be closed with the battery strap 24 by means

of a switch 35 pivoted to the outside of the switch box 12. That portion 36 of the bell and lamp circuits which is common to both is connected to an unlocking relay 37 through a branch circuit 38. The relay 37 70 co-operates with the locking dog 28 for releasing any or all of the cores 25 which may have been brought down into position to lift the arms connected thereto. The releasing relays 37 are all controlled from 75 a releasing switch 37'. When the dog 28 is drawn by its relay 37 out of the path of the core 35, the arm associated therewith swings down by gravity, bringing the core into its normal elevated position, and in 80 this position the core holds the dog mechanically in close relation to the relay coils with the spring 30 under tension. None of the relays or solenoids, however, are maintained energized except when the switches 85 or buttons are operated.

A local contact device 39 is associated with each of the pivoted dogs 28. This contact serves to complete the circuit from the main battery 23 through either the bell 31 or lamp 33, or both of them, depending upon the location of the switch 35, when any one of the cores 25 moves downwardly so as to allow the spring 30 to close such local contact. If, however, the switch 35 95 is free from both of the contacts 33' and 34', as indicated in the diagram, the bell and lamp will both be inoperative even though the local contact 39 may be closed.

The bell 31 is shown arranged within the 100 casing 10, but obviously it may be located elsewhere if desired. The lamp 33 is located preferably upon the rear face of the casing 10 and so related as to cause the light therefrom to be thrown against the face of 105 any one of the arms which may be thrown into operative position.

Having thus set forth a preferred embodiment of the mechanism, the operation of the device may be briefly summarized as follows: The driver of the automobile shown, when about to turn to the left, for example, will give warning to any parties following him by pressing the button or switch 16^b at the switch box conveniently arranged at the 110 steering wheel. The circuit from the battery 23 will be closed, therefore, while the button 16^b is depressed, through the branch circuit 16^c, solenoid 16^a and relay 22 associated with the arm 16. The arm, then, will 115 be swung outwardly through the slot 16' into substantially horizontal position where it will be held as long as desired by virtue of the dog 28 and spring 30. If it is desired for the bell 31 to ring while the arm is thus 120 held displayed, the switch 34' will be closed by the movable switch 35, and if the traveling is at night, when the lamp is desired to 125 glow, the switch 35 will be set to bridge both of the contacts 34' and 32'. The local con- 130

tact 39 will be maintained closed as long as the arm is elevated. After the turn is made, the previously elevated arm will be released by pressing the release contact 37' which will momentarily energize all of the relays 37, hence withdrawing any dog 28 which may be in position to hold a core 25 depressed. The action of the relay 37 in this connection will break the contact 39, stopping the bell and lamp if they are in use. The catch 19 held normally in engaging position by the spring 21 will nevertheless allow the descending arm to snap over and be engaged thereby.

Having thus described my invention, I claim as new and desire to secure by Letters Patent:—

1. The herein described automobile signal apparatus comprising a casing, a series of signal arms pivoted within said casing on a common axis and movable independently of one another in the same direction in parallel planes, a series of solenoids having movable cores, flexible connections between the cores and the several signal arms, selective push buttons for exciting any desired solenoids, a spring operated dog for each core serving to automatically catch and hold the core of any solenoid to maintain the arm in elevated position, a series of magnets associated with said dogs and arranged in parallel, and a single push button serving to energize all of said last mentioned magnets simultane-

ously for releasing any or all of the dogs, substantially as set forth.

2. In an automobile signal apparatus, the combination of a casing having in one side a series of vertical parallel slots, a series of signal arms pivoted within the casing and just within the slots, a series of solenoids having movable cores adjacent the bottom of the casing, each of the arms having secured thereto a sprocket wheel concentric with the axis thereof, a series of chains connected to said movable cores and operating over the several arm wheels, a series of circuits with independent push buttons in which said solenoids are arranged and through which any or all of the arms may be projected outwardly through their slots into display position independently of one another, a catch arranged to coöperate with the free end of each arm to hold it in normal position within the casing, and a quick-acting electromagnet in each of said solenoid circuits serving to act initially upon said catch to release the arm when the solenoid is being energized to swing the arm into display position.

In testimony whereof I have signed my name to this specification, in the presence of two subscribing witnesses.

EDWARD SOULE.
